R. E. WILDER.
TRUCK FRAME.
APPLICATION FILED APR. 25, 1918.

Patented July 2, 1918.

INVENTOR

Ralph E. Wilder.

GEO. E. Thackray
ATTORNEY

UNITED STATES PATENT OFFICE.

RALPH E. WILDER, OF JOHNSTOWN, PENNSYLVANIA.

TRUCK-FRAME.

1,270,908.

Specification of Letters Patent.

Patented July 2, 1918.

Application filed April 25, 1918. Serial No. 230,829.

To all whom it may concern:

Be it known that I, RALPH E. WILDER, a citizen of the United States, and a resident of the city of Johnstown, county of Cambria, and State of Pennsylvania, (whose post-office address is Johnstown, Pennsylvania,) have invented certain new and useful Improvements in Truck-Frames; and I do hereby declare the following to be a full, clear, and exact description of the invention, such as will enable others skilled in the art to which it appertains to make and use the same.

My invention relates to trucks for rail-way cars and particularly to those for freight cars and to that portion known as the side frame and its appurtenances. My truck frame consists essentially of an integral metal plate, formed with the upright portions spaced apart; the top member being integral and the side members bent downwardly therefrom; the end members projecting longitudinally of the frame and provided with bearing surfaces adapted to rest on the tops of the journal boxes; the ends of the side portions extending downwardly and inwardly inclined from the tops of the journal box bearing portions; the bottom portion being substantially horizontal, the whole being provided with openings centrally arranged, of substantially rectangular form to receive the end of the bolster; the lower portion of the opening being provided with a spring seat, and the sides of the opening being provided with bolster guides. The two upright web portions, which are spaced apart, are secured together by means of a bent plate, the flanges of which are riveted near the lower portions of the side members and preferably also to the inclined portions of the side members. I also provide two triangular openings with rounded corners in each side portion, having internally projecting integral stiffening flanges around them. The structural portion of my truck side frame is thus practically composed of one sheet or plate of metal, which is formed or folded together at its upper portion, the downwardly projecting side members being spaced apart and the lower portions secured together by a bent plate secured to both.

Having thus given a general description of my invention I will now, in order to make the matter more clear, refer to the annexed

sheet of drawings which form part of this specification and in which like characters refer to like parts.

Figure 1 is a side elevation of a railway car truck provided with a side frame embodying my invention; Fig. 2 is a vertical longitudinal sectional elevation; Fig. 3 is a top plan view; Fig. 4 is a vertical transverse sectional elevation taken on the line IV—IV of Fig. 3; Fig. 5 is a sectional elevation taken on the line V—V of Fig. 2; and Fig. 6 is an end elevation.

Referring now to the characters of reference on the drawings:—1 is the side frame in general, 2 is the upper portion or top flange, 3 are the sides or webs which are substantially upright, spaced apart and substantially parallel to each other, 4 is the central opening of substantially rectangular outline with rounded corners, the edges of the plate adjacent the opening being provided with integral outwardly extending flanges 5. The webs are further provided with triangular openings 6 with rounded corners, these being provided with inwardly extending flanges 7 formed integral with the web portions. The entire lower portions and inclined side portions of the frame are provided with integral outwardly extending flanges 8. As shown, there are two side plates 3 formed integrally with the top flange 2 and extending downwardly therefrom and substantially parallel to each other, and the lower portion of the truck frame and the inclined side portions are secured together by means of the bent plate 14, the flanges of which adjoin and are riveted to the webs 3 as illustrated, by means of the rivets 15. The rivets 15 are preferably through rivets and are provided with sleeves or thimbles 16 between the flanges to resist the compression when driving and to further stiffen the structure when the rivets are driven. The plate 14 is formed, as shown, with flanges by doubling or folding the plate, and the intermediate part of the outwardly extending portions 22 rests upon the upper surfaces of the flanges 5 and assists in forming the spring seat as illustrated. The portions 22 are of slightly less length than that of the bolster opening as shown. The spring plank 17, which is of channel form, is secured, as illustrated, and riveted through the flanges 5 and the extending portions 22 as shown. Column guides 18 are secured to the flanges 5, these column guides

being formed of pressed plates, as illustrated. The bolster is 19, the springs 20, the 5
brake hanger carriers are 21, the outwardly extending portions of the bent plate are 22, and journal boxes 23 of the usual type are used. Bearing plates 10 are secured to the laterally projecting ends of the truck frame to form seats to bear upon the tops 10
of the journal boxes. Holes 11 are provided in the journal bearing plate 10, and other openings 12 are provided near the ends of the upper flange member 2 through which the journal box bolts 9 may be passed 15
for securing the journal boxes to the truck frame. The usual pedestal tie bar 13 is shown as riveted to the truck frame and secured to the lower portions of the journal boxes by means of the journal box bolts.

Although I have described and illustrated 20
my invention in considerable detail, I do not wish to be limited to the exact and specific details thereof as shown and described, but may use such modifications in, substitutions for, or equivalents thereof, as are 25
embraced within the scope of my invention or as pointed out in the claims.

Having thus described my invention, what I claim and desire to secure by Letters 30
Patent is:

- 30 1. In a truck frame an integral plate forming the top, side and bottom members, the sides of which extend substantially parallel and downwardly from the upper member.
- 35 2. In a truck frame an integral metal plate composing the top, side and bottom members, the top member having longitudinal extensions, the bottom and sides being provided with integral outwardly extending 40
flanges, bearing plates secured to the longitudinal extensions, and a bent plate secured between and to the lower portions of the side members.
- 45 3. In a truck frame an integral metal plate composing the main members, the sides being bent downwardly from the upper portion of the top member, longitudinally extending end portions forming journal bearing portions, and bolster openings in the side 50
members provided with outwardly extending flanges around the edges thereof.
- 55 4. In a truck frame a main member comprising an integral plate forming the top and bottom members and the sides and provided with longitudinal extensions forming journal bearing portions, integral outwardly

extending flanges on the side and bottom portions, and a bent plate with flanges adjacent and secured thereto.

5. In a truck frame an integral metal plate 60 comprising the main structure, provided with longitudinal extending portions forming journal bearings, the side portions being bent downwardly from and extending substantially parallel below the upper portion, the lower portions being provided with externally projecting flanges, bolster openings at the central portion of said side frame provided with integral outwardly projecting flanges surrounding the same, triangular 70
openings adjacent to said central opening, the margins of which are provided with integral inward projections.

6. In a truck frame an integral metal plate 75 comprising the main members composing the upper portion, side portions bent downwardly and extending substantially parallel below the same, substantially horizontal lower portions, inclined side portions, outwardly extending flanges on the lower portions of said frame, the longitudinal extending portion being provided with bearing plates secured to the flanges thereof.

7. In a truck frame an integral metal plate 80 comprising the main members composing an upper portion, side portions bent downwardly and extending substantially parallel below the same, substantially horizontal lower portions, inclined side portions, longitudinally extending end portions, outwardly 90
extending flanges on the lower sides of said frame, the longitudinal extending flanges being provided with bearing plates secured to the flanges thereof, and a bent plate, the flanges of which adjoin and are secured to 95
the lower parts of said side portions.

8. A side frame, the main members of which are formed of a single integral plate comprising a top portion, side portions bent downwardly therefrom, spaced apart and substantially parallel, the lower portions being provided with outwardly projecting flanges, a bent plate provided with flanges adjoining the lower part of the side portions and secured thereto, longitudinal extending upper portions provided with bearing plates secured to the outwardly projecting flanges thereof and adapted to form journal bearings.

In testimony whereof I hereunto affix my 110
signature.

RALPH E. WILDER.
